CLAIM

The ornamental design for an earphone case, as shown and described.

DESCRIPTION

1. Earphone case
2. Earphone case
- 1.1 : Front
- 1.2 : Back
- 1.3 : Left
- 1.4 : Right
- 1.5 : Top
- 1.6 : Bottom
- 1.7 : Perspective
- 1.8 : Front perspective view in an open state
- 1.9 : Perspective view in an open state
- 1.10: Perspective view in an open state with earphones included
- 2.1 : Front
- 2.2 : Back
- 2.3 : Left
- 2.4 : Right
- 2.5 : Top
- 2.6 : Bottom
- 2.7 : Perspective
- 2.8 : Perspective view in an open state
- 2.9: Perspective view in an open state with earphones included

(Continued)

The earphone receiving recesses in **1.8**, **1.9**, and **2.8**, from the outlined edge inward, and the earphones in **1.10** and **2.9**, form no part of the claimed design.

1 Claim, 19 Drawing Sheets
